[57] CLAIM

The ornamental design for a sprayer, as shown and described.

DESCRIPTION

FIG. 1 is a side elevational view of the sprayer of this invention;

FIG. 2 is a side elevational view of the device of FIG. 1, showing the unit from the opposite side of FIG. 1;

FIG. 3 is an end elevational view of the device of FIG. 1, taken from the right side of FIG. 1;

FIG. 4 is an end elevational view of the device of FIG. 1, taken from the left side of FIG. 1;

FIG. 5 is a top plan view of the device of FIG. 1;

FIG. 6 is a bottom plan view of the device of FIG. 1;

FIG. 7 is a view similar to FIG. 5, showing the unit with the spray gun and cup removed;

FIG. 8 is a side elevational view of the removable spray gun and cup unit shown in FIG. 1, received in its holder at the right hand side of FIG. 1. The side opposite the side shown in FIG. 8 is the same;

FIG. 9 is an end elevational view of the spray gun and cup unit of FIG. 8, taken from the right hand side of FIG. 8;

FIG. 10 is an end elevational view of the spray gun and cup unit of FIG. 8, taken from the left side of FIG. 8; and,

FIG. 11 is a bottom plan view of FIG. 8.

The cord is shown fragmented to indicate indeterminate length.
